FIG. 4.

FIG. 5.

Inventor.
Jacob B. Blaw

By Attorney.

UNITED STATES PATENT OFFICE.

JACOB B. BLAW, OF ATLANTIC CITY, NEW JERSEY.

FIRE APPARATUS.

Application filed September 23, 1924. Serial No. 739,277.

To all whom it may concern:

Be it known that I, JACOB B. BLAW, a citizen of the United States, and resident of Atlantic City, county of Atlantic, State 5 of New Jersey, have invented an Improvement in Fire Apparatus, of which the following is a specification.

My invention has particular reference to 10 hose nozzle carrying towers for use in throwing a plurality of streams of water upon a fire without requiring constant attention on the part of the firemen, and, moreover, relates to means for accomplishing this and other purposes when embodied 15 in a truck upon which the nozzle holding devices are mounted and constitute a part.

In carrying out my invention, I provide 20 a suitable truck having a frame work at its upper part similar to a ladder construction, that is, longitudinal members with trans- 25 verse members and to which latter are clamped upright adjustable tower members to the upper end of which there are arranged a plurality of nozzle clamping means 30 for directing and supporting the nozzles in predetermined fixed relations, the upwardly extending tower members being preferably collapsible and so attached to the transverse members of the truck that they may be collapsed and folded down upon the truck at 35 times of transportation.

My invention further comprehends a truck of the above character provided with a longitudinal water main having lateral 40 outlets for providing hose connection with the fire nozzles clamped in the nozzle clamps of the tower and also provided with inlets with which the water supply hose may be connected whereby a water supply may be 45 furnished from fire engines or from high pressure mains.

As a further feature of construction, the truck is provided with transversely arranged frames having secondary fire nozzle clamps at a lower level than the nozzle clamps on the towers, whereby a secondary battery of nozzle throwing streams may be adjusted and be self-supporting at a lower level than the tower nozzles.

50 My invention also comprehends other features of construction which, together with those above enumerated, are more fully described hereinafter and particularly pointed out in the claims.

55 Referring to the drawings: Fig. 1 is a side elevation of a fire truck having my im-

proved water tower construction applied thereto; Fig. 2 is an end elevation of the same looking toward the rear; Fig. 3 is a plan view of the general frame of the truck 60 and the water supply pipes thereon; and Figs. 4 and 5 are elevations of the towers respectively taken from points of view 90° apart, so as to give, in effect, end and side views.

65 2 is the truck and is preferably motor driven. It is provided with a superstructure having transverse bars 3' which may be secured to the truck chassis in any suitable manner, as, for instance, in the downwardly extending side bar portions 3 which may support side operating platforms 8, these being directly attached to the upper members of side bracket portions 7 and adapted to sustain the hosemen when erecting the tower and operating the nozzles. Furthermore, the truck chassis may be provided with a longitudinal water main 9, having at the rear end a plurality of valved inlets 10 by which to receive the water under 70 pressure either by hose connections with a high pressure street main or with fire engines, one such hose connection being shown at 26 in dotted lines in Fig. 2. The forward end of this water main on the truck is provided with lateral branches 11 whose ends open from the sides of the truck and are furnished with valved inlets 12, these inlets being preferably for receiving further water supply in case a large number of 75 streams are to be taken off the fire nozzles supported by the truck, as hereinafter explained. These inlets 12 may, however, act as outlets for supplying water to the fire nozzles when desired. In addition to these 80 lateral branches, there may be a plurality of additional branches 13, each provided with a plurality of valved outlets 14, eighteen such outlets being shown, and from which hose connections may be made to 85 separate fire nozzles as shown in Fig. 2, where hose section 25 supplies fire nozzle 24 and hose section 25^a supplies fire nozzle 24^a, by way of example.

90 Extending upward from and supported by the cross bars 3' are one or more collapsible towers 6, which, when raised, will support a plurality of fire nozzles. The elevated positions of these towers are shown both in solid lines and in dotted lines in 95 Fig. 1, and the collapsed position is also shown resulting from the dotted tower, the 100

collapsing taking place in the direction of the arrow. Referring more specifically to the construction of these towers, they comprise two main frames 15 and 15^a hinged at their upper ends at 17 to a crown-head 16 upon which the fire nozzle holding clamps 18 are adjustably secured, as shown more fully in Figs. 4 and 5. The frames 15 and 15^a are alike and each consists of spreading side uprights secured together in spaced relation by cross bracing and having their lower ends provided with detachable clamps 19 which have transverse holes and adjustable jaws for gripping one of the transverse bars 3' of the truck superstructure. These clamps 19, when securely gripped to the transverse bars, hold the two frames 15 and 15^a in a spread condition at their lower ends; and said frames are further braced by the tie rods 20 which are hooked at their upper ends 21 to the cross bracing of the respective frames and cross each other with their lower ends provided with clamping jaws 23 for detachable attachment also to the transverse bars 3', as shown. These tie rods are further provided with turn-buckles 22 for adjusting their length and enabling them to be tightened when in clamped position.

30 During transportation, it is desirable to collapse the towers so that they lie flat upon the transverse bars 3' and this may be done by detaching the clamps 19 on the bottom of one of the main frames 15^a, for example, from the transverse bar 3' and unhooking both of the tie rods 20, and thereupon folding the two frames 15 and 15^a upon each other and swinging them down in the direction of the arrow Fig. 1, while maintaining the hinge connection of the main frame 15 with the transverse bar 3' to which it is attached. The tie rods 20 may also fold down, while maintaining hinged connection with the transverse bars to which they are respectively attached. It will be manifest that these towers may be quickly erected by simply raising the main frames and spreading them at the bottom, attaching the free frame 15^a to the proper transverse bar 3', hooking the tie rods 20 in position and tightening them by the turn-buckles 22.

35 The crown heads 16 contain a plurality of sockets in which separate fire nozzle clamps 18 are adjustably supported so as to have universal adjustment to enable the streams to be projected at any angle or elevation desired. I have shown a desirable form of nozzle clamp which I have found excellently suitable to the purpose, but I do not restrict myself to the special form of nozzle clamp shown. The nozzles 24 are coupled with the outlets 14 of the branches of the water main on the truck by hose sections 25, one of which is shown. This arrangement permits free adjustment of the

fire nozzles since the hose sections freely yield to compensate for change of position in the nozzles. These nozzles or any of them may be supplied with water from the main hose leading from the fire engines or high pressure mains, but I prefer in all cases to utilize the water main on the truck and the short flexible hose sections 25 and 25^a leading therefrom to the nozzles, as being more easy of adjustment and less liable to displacement.

40 While the truck is provided with one or more towers, each with a plurality of nozzle clamps, additional nozzle clamps 18^a may be adjustably secured to the bracket frames 7, one of which nozzle clamps is shown in Fig. 2, the nozzle 24^a thereof being supplied with water by a short hose section 25^a coupling the nozzle with one of the outlets 14. These bracket frames 7 may be of a permanent construction where they support the longitudinal platforms 8, otherwise they may be in the form of detachable nozzle supports of the character more fully shown in my application Serial Number 680,094, filed December 12, 1923, in which case they would be detachably clamped to the downwardly extending side bar portions 3 of the superstructure of the truck frame.

45 It is further pointed out that the transverse bars 3' correspond to the rounds of a ladder and hence, if the truck is required to carry a ladder in a horizontal position, the towers may be clamped to the ladder rounds instead of the transverse bars 3', this utilization of the ladder for supporting the nozzle clamps being set out in my applications Serial Number 690,419, filed February 4, 1924, and Serial Number 680,094, filed December 12, 1923, and hence so far as the tower construction itself is concerned, I do not restrict myself as to its base of support.

50 It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

55 Having now described my invention, what I claim as new and desire to secure by Letters Patent is:

60 1. In a fire apparatus, a truck wherein there are provided a plurality of transverse bars, combined with a pair of frames hinged at the top relatively to each other and in connection with a nozzle holding crown, said frames having at each of their lower ends a plurality of clamping means widely separated for making attachments with the

120 125 130

transverse bars and whereby they are hingedly connected so that by unclamping one of the frames the tower may be collapsed and folded down upon the truck, and a plurality of hose nozzle carrying clamps each independently adjustable upon the nozzle holding crown.

2. The invention according to claim 1, wherein further, the respective frames constituting the tower are each provided with a tie rod connected at a point intermediate of the top and bottom of the frame to which it is attached, and said tie rods provided at their lower and free ends with clamping means whereby the tie rods cross each other and are detachably clamped to the transverse bars at a distance from the clamping means of the tower frames to which they are connected.

20 3. The invention according to claim 1, wherein the tower is collapsible in the direction between the front and rear of the truck and the plurality of nozzle clamps in spaced relation are arranged upon the crown in a plane corresponding to the length of the truck whereby the fire nozzles may have freedom for adjustable transverse positioning to cause the plurality of streams to be thrown transversely to the length of the truck.

30 4. The invention according to claim 1, wherein further, fire nozzles are provided for the nozzle clamps, the truck is provided with water mains with branch outlets and one or more inlets, and flexible hose connections between the branch outlets and the respective fire nozzles, the inlets adapted to receive water from a suitable source and delivering it through the water main to the respective nozzles and hose leading thereto.

40 5. The invention according to claim 1, wherein there is provided at the side of the

truck a plurality of laterally extending frames having at their outer ends nozzle holding clamps, and suitable means carried on the truck for supplying water to fire nozzles detachably clamped in the respective nozzle clamps of both the tower and the lateral frames.

45 6. The invention according to claim 1, wherein further, the truck is provided on each side of the tower with an operating platform.

50 7. The invention according to claim 1, wherein further, the two frames of the tower are further rigidly secured in position by means of crossing tie rods respectively attached to the two frames and by means of which tension is applied thereto in opposite directions, said tie rods being adapted for adjusting the tension applied.

55 8. A device of the character stated, comprising a tower structure comprising two parts jointed together at one end in connection with a nozzle clamp holding head said parts having at their other end a plurality 60 of widely spaced adjustable clamping means by which they may be clamped on transverse bars.

65 9. The invention according to claim 8, wherein further, each of the parts is provided with a jointed tie rod having at its free end an adjustable clamp.

70 10. The invention according to claim 8, wherein further, each of the parts is provided with a jointed tie rod having at its 75 free end an adjustable clamp, said tie rods being extensible in the direction of their length.

In testimony of which invention, I hereunto set my hand.

JACOB B. BLAW.
